CARTRIDGE FEED BELT FOR MACHINE GUNS

James A. Hendley, Middletown, Conn., assignor to
The Russell Manufacturing Company, Middletown, Conn., a corporation of Connecticut

Application August 12, 1943, Serial No. 498,291

4 Claims. (Cl. 89—35)

1

This invention relates to improvements in cartridge feed-belts for machine guns.

One object of this invention is to provide an improved cartridge feed-belt unit so that a plurality of such units can be readily connected together by cartridges.

Another object of this invention is to provide an improved process of making the foregoing cartridge feed-belt unit.

With the above and other objects in view, as will appear to those skilled in the art from the present disclosure, this invention includes all features in the said disclosure which are novel over the prior art.

In the accompanying drawings, in which certain ways of carrying out the invention are shown for illustrative purposes:

Fig. 1 is an elevational view of a cartridge feed-belt made in accordance with the present invention and illustrating cartridges in some of the pockets thereof;

Fig. 2 is an enlarged sectional view on the line 2—2 of Fig. 1;

Fig. 3 is an enlarged sectional view on the line 3—3 of Fig. 1;

Fig. 4 is an enlarged elevational view of one of the feed-belt units shown in Fig. 1;

Fig. 5 is an edge view of Fig. 4;

Fig. 6 is a fragmental view similar to Fig. 2 of a modified construction;

Fig. 7 is an elevational view of a woven cartridge feed-belt blank from which the unit in Fig. 4 is made;

Fig. 8 is a front edge view of Fig. 7;

Fig. 9 is a view similar to Fig. 7 after the blank of Fig. 7 has had plastic applied to such portions thereof as are to be cut away to form the unit shown in Fig. 4, and with broken-line indications as to where the cuts are made to produce the unit of Fig. 4, and with a broken-line outline of a pocket-forming finger in a pocket;

Fig. 10 is a longer section of a woven cartridge feed-belt blank similar to Fig. 7; and

Fig. 11 is a view similar to Fig. 10 after plastic has been applied along the entire belt-blank of Fig. 10 and with broken-line indications indicating the lines of cut by which a plurality of units each similar to the unit shown in Figs. 4 and 5 is produced, but having plastic along the entire surface instead of along only part of the surface as shown in Fig. 4.

In the description and claims, the various parts and steps are identified by specific names for convenience, but they are intended to be as generic in their application as the prior art will permit.

In carrying out the invention in the particular way illustrated in Figs. 1 to 9 of the drawings, the cartridge feed-belt 20 is formed of a group or plurality of successive feed-belt units

2

21. Each unit 21 shown in the drawing is formed from a blank 22 shown in Figs. 7 and 8 and which has two plies of fabric 23 and 24 and is made in any suitable way as, for example, in accordance with my Patent No. 2,081,072 granted on November 17, 1936.

In making a cartridge feed-belt unit 21 like that shown in Figs. 4 and 5 from the blank 22 shown in Figs. 7 and 8, plastic is first applied to the two end-portions 25 and 26 as shown by stippling on Fig. 9, after which portions are cut away as indicated by broken lines, to leave the central tongue-loop 27 (Fig. 4) at one end of the blank and the spaced-apart tongue-loops 28 and 29 with a strap-portion 30 connecting the outer ends of the spaced-apart tongue-loops 28 and 29 together.

In making a woven fabric cartridge feed-belt for machine guns, the various pockets 31 thereof are made of a carefully-predetermined size so that when a cartridge is forced into a pocket, the cartridge will be gripped with a predetermined strong grip that will be proper to hold it in place and yet will permit the extractor of the

mechanism of the machine gun to properly extract the cartridge from the belt. In applying plastic to the end portions of the belt-section or blank or unit, the plastic is applied to opposite outside faces of the plies in any suitable way. But in applying plastic to the woven fabric material, the plastic gets between the various strands and between the fibers of the strands and thereby interferes with the normal stretching ability of a pocket to which plastic has been applied. Therefore in order that such plastic-treated pockets or the tongue-loops 27, 28 and 29 made from such pockets and which are to be utilized to connect two units together by means of inserting a cartridge through overlapped tongue-loops, may be large enough to properly receive cartridges, it is necessary to prestretch or preform such pockets during the application of the plastic to the fabric. This can be done by forcibly inserting a pocket-forming finger 32 into each of the end-pockets of a blank to which plastic is to be applied as is illustrated in broken-line outline at the right-hand end of Fig. 9. Plastic can then be applied in any suitable way as, for example, by applying suitably heated thermoplastic material by any suitable means.

Or the plastic material can be formed as a solution by means of a solvent in a well-known way and applied on as by brushing or otherwise and permitting the solvent to evaporate out to leave the plastic in place. The plastic used will preferably be such as has pliability when cold so that the parts of the belt to which it is applied still will retain considerable pliability and flexibility. But the plastic may have sufficient forming characteristics so that such pockets as have

been stretched and have had plastic applied thereto, will have a form such as illustrated for the loops at the right- and left-hand ends of Fig. 5.

After the forming fingers 32 have been removed and the plastic has acquired its final solid condition, the belt-blank 22 such, for example, as is illustrated in Fig. 9 will have portions cut away by dies or otherwise to leave the tongue-loops 27, 28 and 29 as illustrated in Fig. 4.

Instead of applying plastic only to such pockets as are to be formed into the tongue-loops at the opposite ends of the belt-unit, the plastic can be applied along the entire length of both opposite faces of a belt-blank instead of merely on opposite faces of the end-pockets of a belt-blank. In this case, however, in order to avoid the need of any pre-stretching device such as 32 illustrated in Fig. 9, which would need to be inserted into each of the pockets throughout the length of the belt or belt-blank, the pockets can be woven sufficiently larger than they would otherwise be woven and the plastic can be applied upon the opposite faces of the belt-blank without having any forming- or stretching-fingers therein, since, inasmuch as the pockets will be woven somewhat larger in this case than would ordinarily be true, it is not necessary that the pockets stretch so much upon the insertion of the cartridges, and therefore the pockets can be of just such size that the plastic on being applied to the opposite faces of the belt just bring about sufficient interference with stretch of the pockets so that when cartridges are inserted they will be gripped to just the desired proper degree.

In applying plastic along the entire length of both faces of a belt-blank 33 such as illustrated in Fig. 10, the plastic 34 is applied thereon throughout as illustrated in Fig. 11 by the stippled showing over the entire surface thereof, and then the belt is cut up into units or sections having tongue-loops at the opposite ends of each unit or section in a similar manner as that illustrated in Fig. 4, as is indicated by the broken lines on Fig. 11.

Where belt-units are made with a small number of complete pockets therein, such, for example, as from one on up to possibly twenty-five or more, upon such belts being filled with cartridges and having each central tongue-loop overlap and extend between the spaced-apart tongue-loops of an adjacent similar feed-belt unit and the overlapping tongue-loops connected by a cartridge extending through all three of them, a cartridge feed-belt for machine guns can be formed of belt-units which will be dispersible upon passing through the machine gun. In other words, as the machine gun is fired and the belt passes out the far end of the feed-mechanism, the units of the belt become successively disconnected as each cartridge is pulled out from overlapping tongue-loops which hold each two adjacent feed-belt units together, thus permitting the outermost unit to fall away as is particularly useful upon airplanes. For many other uses such, for example, as in tanks, upon ships, and in fixed locations on land, longer belt-units can be used. Each unit, for example may have a length up to one or two hundred cartridges or more. Thus where a gunner has fired all except, say, ten cartridges of a belt-unit, and he desires to be prepared for continuously firing a large number of cartridges at the next need for firing, it is merely necessary to connect the tongue-loop or tongue-loops at the rear end of the belt-unit in the gun,

with the complementary tongue-loops or tongue-loop of the front end of another belt-unit that is all filled with cartridges, so that the gunner can have available more than one hundred cartridges for the next emergency.

The invention may be carried out in other specific ways than that herein set forth without departing from the spirit and essential characteristics of the invention, and the present embodiment is, therefore, to be considered in all respects as illustrative and not restrictive, and all changes coming within the meaning and equivalency range of the appended claims are intended to be embraced therein.

I claim:

1. A cartridge feed-belt unit for machine guns comprising: a feed-belt unit formed of two plies of woven fabric and having at least one flexible complete cartridge-receiving pocket and a central tongue-loop at one end and spaced-apart tongue-loops at the other end with a strap-portion connecting the outer ends of said spaced-apart tongue-loops together; the central tongue-loop being constructed and arranged to overlap and extend between the spaced-apart tongue-loops of an adjacent similar feed-belt unit and have a cartridge extend through the said overlapped loops to connect said two units together; and the spaced-apart tongue-loops of said first-mentioned feed-belt unit being constructed and arranged to be similarly connected to the central tongue-loop of another similar feed-belt unit, and each said tongue-loop being flexible and formed as an integral part of said feed-belt unit and of portions of said two plies of woven fabric of substantially equal length.

2. A cartridge feed-belt unit for machine guns comprising: a fabric feed-belt unit formed of two plies of woven fabric and having at least one flexible complete cartridge-receiving pocket and a flexible plastic-treated central tongue-loop at one end and flexible plastic-treated spaced-apart tongue-loops at the other end with a strap-portion connecting the outer ends of said spaced-apart tongue-loops together; the central tongue-loop being constructed and arranged to overlap and extend between the spaced-apart tongue-loops of an adjacent similar feed-belt unit and have a cartridge extend through the said overlapped loops to connect said two units together; and the spaced-apart tongue-loops of said first-mentioned feed-belt unit being constructed and arranged to be similarly connected to the central tongue-loop of another similar feed-belt unit, and each said tongue-loop being flexible and formed as an integral part of said feed-belt unit and of portions of said two plies of woven fabric of substantially equal length.

3. The process of making cartridge feed-belt units for machine guns comprising: making a machine gun feed-belt unit blank formed of two plies of woven fabric and having a plurality of cartridge-receiving pockets, and from which can be cut at least one feed-belt unit having at least one flexible complete cartridge-receiving pocket and a central tongue-loop at one end and spaced-apart tongue-loops at the other end with a strap-portion connecting the outer ends of said spaced-apart tongue-loops together, and the central tongue-loop being constructed and arranged to overlap and extend between the spaced-apart tongue-loops of an adjacent similar feed-belt unit and have a cartridge extend through said overlapped loops to connect said units together, and the spaced-apart tongue-loops of said first-

mentioned feed-belt unit being constructed and arranged to be similarly connected to the central tongue-loop of another similar feed-belt unit; and cutting at least one feed-belt unit from said blank by cutting away opposite end portions of a pocket at one end to leave the central portion of said pocket to form said central tongue-loop, and by cutting away the central portion of a pocket at the other end to leave spaced-apart opposite end portions of said pocket to form said spaced-apart tongue-loops with a strap-portion connecting the outer ends of said spaced-apart tongue-loops together, each said tongue-loop being flexible and formed of portions of said two plies of woven fabric of substantially equal length.

4. The process of making cartridge feed-belt units for machine guns comprising: making a fabric machine gun feed-belt unit blank formed of two plies of woven fabric and having a plurality of cartridge-receiving pockets, and from which can be cut at least one feed-belt unit having at least one flexible complete cartridge-receiving pocket and a central tongue-loop at one end and spaced-apart tongue-loops at the other end with a strap-portion connecting the outer ends of said spaced-apart tongue-loops together, and the central tongue-loop being constructed and arranged to overlap and extend between the spaced-apart tongue-loops of an adjacent similar feed-belt unit and have a cartridge extend through said overlapped loops to connect said units together, and the spaced-apart tongue-loops of said first-mentioned feed-belt unit being con-

structed and arranged to be similarly connected to the central tongue-loop of another similar feed-belt unit; treating with flexible plastic at least such pocket portions as are to form severed longitudinal edges of tongue-loops; and cutting at least one feed-belt unit from said blank by cutting away opposite end portions of a pocket at one end to leave the central portion of said pocket to form said central tongue-loop, and by cutting away the central portion of a pocket at the other end to leave spaced-apart opposite end portions of said pocket to form said spaced-apart tongue-loops with a strap-portion connecting the outer ends of said spaced-apart tongue-loops together, each said tongue-loop being flexible and formed of portions of said two plies of woven fabric of substantially equal length.
